FOLDING TRAY CONSTRUCTION

Rollie B. Nawman, Piedmont, Calif., assignor to Benner-Nawman, Inc., Oakland, Calif., a corporation of California

Filed Mar. 8, 1962, Ser. No. 178,297
5 Claims. (Cl. 211—132)

This invention relates to a folding tray construction and more particularly to a folding tray construction which is particularly adapted for carrying loaves of bread and the like.

Folding trays have heretofore been provided. However, such folding trays have not been satisfactory because they cannot be stacked with noncollapsible trays or nonfolding trays already in the market. In addition, it has been found that even if such trays can be stacked with the noncollapsible and nonfolding trays on the market, they are of such a size they cannot be stored in the same storage space in bakeries, trucks and the like. There is therefore a need for a new and improved folding tray.

In general, it is an object of the present invention to provide a folding tray which is relatively simple and inexpensive to manufacture.

Another object of the invention is to provide a folding tray in which the bails can be readily moved between upright and folded positions.

Another object of the invention is to provide a folding tray of the above character in which the trays can be readily stacked one above the other when the bails are in an upright position or in a folded position.

Another object of the invention is to provide a folding tray of the above character in which the trays can be stacked one above the other with the bails in an upright position by sliding the lower portions of the trays on the bails of the tray beneath.

Another object of the invention is to provide a folding tray of the above character in which the trays can be stacked either with the bails in folded or upright positions with noncollapsible or nonfolding trays.

Another object of the invention is to provide a folding tray construction of the above character which can be stored in spaced dimensions for noncollapsible or nonfolding trays already on the market.

Additional objects and features of the invention will appear from the following description in which the preferred embodiment has been set forth in detail in conjunction with the accompanying drawings.

Referring to the drawings:

FIGURE 1 is an isometric view of a folding tray incorporating my invention.

FIGURE 2 is an enlarged cross-sectional view taken along the line 2—2 of FIGURE 1.

FIGURE 3 is an enlarged cross-section view similar to FIGURE 2 showing the bail in a folded position.

FIGURE 4 is a partial side elevational view in cross-section of a pair of trays stacked one above the other with the bails in an upright position.

FIGURE 5 is a partial cross-section view taken along the line 5—5 of FIGURE 4.

FIGURE 6 is a partial side elevational view in cross-section of a pair of trays stacked one above the other with the bails in a folded position.

FIGURE 7 is a partial cross-sectional view taken along the line 7—7 of FIGURE 6.

FIGURE 8 is an isometric view showing the utilization of my folding tray with a noncollapsible or nonfolding tray.

FIGURE 9 is a partial cross-sectional view taken along the line 9—9 of FIGURE 8.

2

In general, my folding tray construction consists of a rectangular framework comprised of a pair of spaced parallel substantially vertical side walls and a pair of spaced parallel substantially vertical end walls. The framework is also provided with a bottom wall portion extending around the perimeter of the framework and having runner-like means depending therefrom. A pair of spaced bails are pivotally mounted in the framework adjacent two of the spaced parallel walls for movement between upright and folded positions towards and away from the adjacent walls. The upper extremities of the bails are formed to provide runner-receiving means extending the length of the adjacent walls to permit stacking of the trays one above the other when the bails are in upright position. The runner receiving means is formed so that the trays can be loaded by sliding the same sideways in the runner-receiving means.

As shown in the drawings, my folding tray construction consists of a generally rectangular framework 11 which is formed by a pair of spaced parallel ends 12 and spaced parallel sides 13. The ends and sides forming the framework 11 are formed of any suitable material such as cold rolled steel and can have the same general configuration as shown in the drawings. Thus, the end and sides 12 and 13 are provided with vertical portions 12a and 13a, respectively, which form vertical side walls and with horizontal portions 12b and 13b, respectively, which form bottom wall portions. Horizontal grooves or recesses 12c and 13c, respectively, are formed in the ends and sides adjacent the horizontal portions 12b and 13b to receive a liner as hereinafter described.

The horizontal or bottom wall portions 12b and 13b of the ends and sides are provided with depending U-shaped runner portions 12d and 13d which are formed integral therewith and which are spaced inwardly from the vertical portions 12a or 13a of the associated wall. As can be seen from the drawing, these U-shaped runner portions extend around the entire perimeter of the bottom portion of the frame 11. The ends and sides are also provided with outwardly and downwardly turned portions 12e and 13e to reinforce the side walls and also to provide rounded upper surfaces for the ends and sides.

A pair of diagonal reinforcing straps 16 are secured to the corner portions of the horizontal portions 12b and 13b of each of the corners of the rectangular frame by suitable means such as spot welding as shown in the drawings. These straps, in addition to reinforcing the framework, also serve to provide a support for the liner (not shown) which is placed in the framework so that the edges of the liner seat within the recesses 12c and 13c of the end sides so that the same are retained therein during movement of the tray.

The folding tray also includes a pair of substantially U-shaped carrying bails 21 formed of a suitable rod-like material. The bails are pivotally mounted in the framework adjacent the ends 12 for movement toward and away from the ends about an axis which is parallel to the ends. The lower extremities of the bails can be pivotally mounted in any suitable manner such as by means of brackets 22 substantially in the form of right angles which are mounted in the corners of the rectangular framework 11 and secured to the horizontal bottom wall portions 12b and 13b and the vertical wall portions 12a of the ends, as shown particularly in FIGURE 4. A cut-out 23 is provided in each of the brackets and is adapted to receive a lower extremity of one end of the bails 21. The bails 21 are provided with portions 21a which extend in a direction which is parallel to the end wall portions 12a and which are held in position against the ends of the framework by curved portions 22a formed in the brackets 22.

The bails are provided with substantially straight vertical portions 21b which, when the bails are in an upright position, extend upwardly vertically in a direction which is at right angles to the portions 21a. As can be seen from FIGURE 1, the portions 21b have a substantial length and are connected to looped portions 21c and 21d. The looped portions 21d are joined by an interconnecting portion 21e which extends in a direction which is at right angles to the portions 21b of each of the bails. The looped portions 21c and 21d are formed in such a manner that together they extend through an angle of 450° from the portions 21b to the portion 21e. In addition, the portions 21c and 21d are spaced apart a sufficient distance so that the runner portions 12d of the framework of the tray above can be received between the same. Since this is the case, it can be seen that the portion 21e is positioned inwardly from the vertical end wall 12a so that it will be disposed on the inner side of the runner portion 12d of the framework of the tray above as shown particularly in FIGURE 4. Thus, in effect, it can be seen that the bails 21 are formed in such a manner that they provide a recess in the upper extremities thereof which extends substantially the entire length of the end wall of the tray and is positioned immediately inwardly from the end wall of the tray so that it is adapted to receive the inwardly disposed runner portions 12d of the tray above as shown particularly in FIGURE 4.

Means is provided for retaining the bails 21 in an upright position and consists of raised portions or abutments 24 formed in the vertical side wall portions 13a of the sides. As can be seen particularly from FIGURE 2, the raised portions or abutments 24 are spaced from the vertical end walls so that the vertical portions 21b of the bail can be received between the raised portion and the end wall. Thus, the bails are retained in an upright position. To facilitate this retention, the bails can be formed of spring steel so that they are sprung into engagement with the vertical side walls.

The bails 21 can be readily moved to a folded position merely by urging the same inwardly by the hand to cause the lower extremities of the bails to be cammed inwardly by the abutments 24 to clear the abutments, after which the bails can be readily folded into a position so that they lie within the confines of the framework 11.

Use of my folding trays can now be briefly described as follows. Let it be assumed that it is desired to stack a plurality of the folding trays with the carrying bails 21 in an upright position. If the bails are not already in an upright position, they can be readily moved to an upright position by merely lifting the bails upwardly and outwardly or in other words by moving the bails with both hands towards and into engagement with the vertical end walls 12 so that they are retained in a vertical position by the abutments 24.

At the same time that the bails are being moved to an upright position, the tray can be lifted and stacked on top of another tray on which the bails have already been raised by positioning the runner portions associated with the end walls 12 into the recesses formed by the looped portions 21c and 21d of the bails of the tray below and then sliding the tray sidewise onto the other tray until the runner portions 13d associated with the opposite side wall drops over the looped portions 21c and 21d of the bails to retain the tray on the bails of the tray below. The depending runner portions 13d provided on the side walls and engaging the side margins of the bails of the tray below prevent lateral movement of the trays with respect to each other, whereas seating of the runner portions 12d between the looped portions 21c and 21d of the bails of the tray below prevent longitudinal movement of the trays with respect to each other.

When the trays are stacked in this manner, they can be filled with bread or other suitable merchandise prior to or after stacking. The bails will serve to support the tray above in the proper position so that the bread or

other commodity carried in the tray will not be crushed. At the same time that construction of the bails and the framework is such that there will not be undue lateral or longitudinal shifting of the trays with respect to each other.

Now let it be assumed that it is desired to stack the trays with the bails in the folded position. If the bails are in an upright position, they can be readily moved to a folded position by using both hands to grasp both bails and pushing the upper extremities of the bails away from the end walls to thereby cause the abutments to cam the lower extremities of the bails inwardly so as to clear the abutments, after which the bails can be dropped or lowered into the framework.

As soon as the bails have been folded, the trays can be stacked one above the other as shown in FIGURE 6 with the runner portions of the framework of the tray above readily seating within the upper margins of the framework as shown particularly in FIGURE 6. Again, the runners cooperating with the framework of the tray below serve to prevent substantial longitudinal and lateral movement of the trays with respect to each other. It can be seen that the bails 21 when folded are in such a position that they do not interfere with the stacking of the trays.

One of the primary advantages of the folding tray which is shown in the drawings is that it can be utilized in conjunction with a type of bread tray which has been marketed for a number of years under the name of "Deltra" and which is similar to the trays shown in Patent No. 2,688,420 and No. 2,801,766. This tray 26, as can be seen from the patents and from the drawing in FIGURES 8 and 9, is of the non-collapsible or nonfoldable type and consists of spaced upper and lower rectangular frameworks 27 and 28 which are maintained in a predetermined vertically spaced apart relationship by right angle corner pieces 29. The lower rectangular framework 28 is provided with a depending runner portion 28a which extends around the perimeter of framework as shown in FIGURES 8 and 9.

As can be seen from FIGURE 8, my folding trays can be stacked with the "Deltra" without any difficulty. Thus, the runner portion 28a of the "Deltra" is readily received within the upper extremities of the bails 21 between the portions 21c and 21d. The runner portion 28a of the bottom framework also engages the side margins of the bails to prevent lateral movement of the "Deltra" with respect to my folding tray. The runner portions 12d and 13d of my tray also readily fit within the upper rectangular framework 27 of the "Deltra" in a manner to prevent substantial lateral and longitudinal movement of my folding tray with respect to the "Deltra."

In addition to being usable with "Deltras," my folding tray also has the additional advantage that it has the same overall rectangular frame dimensions as the "Deltra" so that my folding tray can be stored in compartments which have been dimensioned for the receipt of "Deltras." This has the great advantage in that it is possible for bakeries already using "Deltras" to readily assimilate the folding trays without changing any of the apparatus or equipment utilized for handling the "Deltras." The use of my folding trays is desirable in that they require much less space than "Deltras" when the bails are in a folded position.

It is apparent from the foregoing that I have provided a new and improved folding tray which has many advantages over the folding trays heretofore provided. My new improved folding tray is relatively simple in construction and can be economically manufactured. Its construction is such that it can be readily integrated with conventional trays already in use.

I claim:

1. In a folding tray, a framework comprised of a pair of spaced parallel substantially vertical side walls and a pair of spaced parallel substantially vertical end walls, the framework also being comprised of bottom wall portions extending around the entire perimeter of the framework

and having substantially continuous runner-like means depending from the same, the runner-like means being positioned inwardly from the side and end walls, and a pair of spaced substantially U-shaped bails pivotally mounted in the framework adjacent two of the spaced parallel walls for movement between upright and folded positions towards and away from said adjacent walls, the outer extremities of the bails being formed to provide runner receiving means extending the length of said adjacent walls to permit stacking of the trays one above the other when the bails are in an upright position, said runner receiving means being in the form of curved spaced pairs of portions with each of said pairs forming a runner-receiving recess extending in a direction parallel to said adjacent walls.

2. A folding tray as in claim 1 wherein said runner receiving means is formed so that the trays can be stacked one above the other by sliding the runner-like means on the runner-receiving means of the bails of the tray below.

3. In a folding tray, a framework having a pair of spaced parallel substantially vertical side walls, a pair of spaced parallel substantially vertical end walls, and bottom wall portions secured to the side and end walls and extending inwardly from the side and end walls in a direction at right angles to the side and end walls, the bottom wall portions being formed with substantially U-shaped runners depending from the bottom wall portions and being positioned inwardly from the side and end walls, and a pair of spaced substantially U-shaped bails pivotally mounted

in the framework adjacent to a pair of said spaced parallel walls for movement between upright and folded positions towards and away from said adjacent walls, the upper extremities of the bails being formed to provide open-ended recesses extending in a direction parallel to said adjacent walls to permit stacking of the trays one above the other when the bails are in an upright position with the runners in the tray above being adapted to be disposed in the runner-receiving means of the bails of the tray below, said runners being adapted to seat within the upper margin of the framework of the tray below when the bails are in a folded position.

4. A folding tray as in claim 3 wherein the corners of the upper extremities of the bails are formed by a pair of integral spaced looped portions which are spaced apart to form said recesses for receiving the runners of the tray above when the bails are in an upright position.

5. A folding tray as in claim 4 wherein the pair of looped portions on each corner of each of the bails extends through an angle of approximately 450°.
